DESIGN FOR A COMBINATION WAXING, SPREADING, AND POLISHING DEVICE

John Macree, Forest Hills, and Walter Paul
Gerhardt, Maspeth, N. Y.

Application April 12, 1947, Serial No. 138,334

Term of patent 14 years

(Cl. D9—2)

To all whom it may concern:

Be it known, that we, John Macree, a citizen of the United States, residing at Forest Hills, county of Queens, city and State of New York, and Walter Paul Gerhardt, a citizen of the United States, residing at Maspeth, county of Queens, city and State of New York, have invented a new, original, and ornamental Design for a Combination Waxing, Spreading, and Polishing Device, of which the following is a specification, reference being had to the accompanying drawing, forming part thereof, wherein:

Fig. 1 is a side view of a combination waxing, spreading and polishing device showing my new design.

Fig. 2 is a top plan view thereof.

Fig. 3 is a front end view thereof; and

Fig. 4 is a bottom plan view thereof.

We claim:

The ornamental design for a combination waxing, spreading, and polishing device, as shown,

JOHN MACREE.

WALTER PAUL GERHARDT.
